Attorney

UNITED STATES PATENT OFFICE.

DAVID P. DODD, OF FORT WORTH, TEXAS, ASSIGNEE TO FRANK B. WYATT, OF FORT WORTH, TEXAS.

MOTION-PICTURE MACHINE.

1,286,874.

Specification of Letters Patent.

Patented Dec. 3, 1918.

Application filed June 25, 1917. Serial No. 176,744.

To all whom it may concern:

Be it known that I, DAVID P. DODD, a citizen of the United States, residing at Fort Worth, in the county of Tarrant and State of Texas, have invented certain new and useful Improvements in Motion-Picture Machines, of which the following is a specification.

My invention relates to improvements in motion picture machines and more particularly to means for automatically shutting the lights off the head or film operating part of the machine; and the object is to provide a simple mechanism for cutting off the light from the head of the machine in case of accident, as when the film breaks. It is well known that when a film breaks it is very frequently ignited immediately by the strong light which is coming from the lamp. I have provided means for intercepting the light beams automatically as soon as the film breaks and thus prevent a burning of the film. The same device will cut off the light whenever the machine stops. The advantages are that the danger of a conflagration is avoided and the burning of the film is prevented. The burning of the film produces a dense black smoke and a deadly poisonous gas. All of such consequences are avoided by a simple inexpensive apparatus. Other objects and advantages will be fully explained in the following description and the invention will be more particularly pointed out in the claim.

Reference is had to the accompanying drawings which form a part of this application.

Figure 1 is a plan view of a motion picture machine with a part of the frame of the head shown in section. Fig. 2 is a portion of the film side of the machine shown in sectional elevation. Fig. 3 is a portion of the governor side of the machine reversed as compared with Fig. 1 shown in broken sectional elevation. Fig. 4 is a detail side view of the film gate or aperture gage. Fig. 5 is a face view of the same. Fig. 6 is a detail view of the shutter mounted on the cone of the lamp for cutting off the light. Fig. 7 is a detail view of the electrical devices for breaking the circuit to stop the motor in case of accident.

Similar characters of reference are used

to indicate the same parts throughout the several views.

For the purpose of illustrating the invention, a machine, such as is in ordinary use, is shown, but it must be understood that the apparatus is adaptable to machines of different types.

The lamp house 1 is shown with the usual cone 2 on which the shutter 3 is pivotally mounted. I provide means for supporting the shutter 3 in position to drop of its own weight when the support is removed. An electro-magnet 4 is mounted on and insulated from the cone 2 and provided with an armature 5 which supports the shutter 3. When the magnet 4 is energized, the armature 5 will be drawn from under the shutter 3 which will then immediately fall. Means are provided for directing a current of electricity through the magnet 4. A transformer 6 is shown connected with a source of electricity for reducing the current to about the capacity of one dry cell battery. It is apparent that a dry-cell battery would accomplish the same purpose. On wire 7 is connected to the transformer 6 and to the magnet 4. Another wire 8 is connected to the other pole of the transformer and runs through the lower part of the head and is connected to an insulated plate 9 and then continued on to and connected to a doubled prong spring 10 which is insulated from the head by a plate 11 and a plate 12, the spring 10 being clamped between the two insulation plates 11 and 12 by screws 13 which are used to hold a steel plate 15 which bears against the film 14. The insulation plate 11 is extended down below the gate and secured in place by a bar 16 and screws 17, an opening being made through the plate 11 for the operation of the springs 10. The springs 10 bear against a steel plate 18 which is a guide for holding the film straight or flat as the film is passing the gate. It is shown how the springs 10 are insulated from the machine on one side. The film 14 forms the insulation on the other side of the springs 10 and the steel plate 18, thus preventing the steel plate 18 and the springs 10 from being in electrical connection with the other side 19 of the film guide or passage way. A pivoted arm 20 carrying a roller 21, is electrically connected with the machine frame at 22. The machine

frame is metal. The arm 20 is adapted to drop on the plate 9 should the film break. Normally the film will hold the arm 20 out of electrical connection with the plate 9.

5 The wire 8 is further extended and connected to an insulated plate 23 which is mounted on the opposite or mechanical side of the machine. A lever 24 is pivotally connected to the governor 25 and fulcrumed on the 10 side of the machine. When the machine stops and the governor 25 drops, moving downwardly on the shaft 40, this will cause the lever 24 to make electrical connection with the plate 23. The governor 25 and the 15 lever 24 are electrically grounded on the machine frame. The lamp house 1 and the machine head are electrically connected by the metallic frame piece 26. The electrical connection between the machine head 39 and the 20 lamp house may be made in any other suitable manner.

The film comes in the head 39 between the rollers 28 at the upper part of the machine head and goes out between the rollers 27 25 at the lower part of the head. In case of a break in the film, the circuit would be closed by the plate 18 coming in contact with the plate 19 or between the arm 20 and plate 9 because the arm 20 would fall on the 30 plate 9 in case of a break of the film 14. This would close the circuit and energize the magnet 4 and then close the shutter 3. When the shutter falls, it will come to rest against a stop 29 for shutting off the light 35 from the machine head. In case the machine should stop, the governor 25 will drop and cause the lever 24 to make electrical connection with the plate 23. This will also close the circuit and energize the magnet 4 40 which operation would cause the shutter 3 to drop and shut off the light from the machine head. Shutting off the light will prevent the film from igniting. When the shutter 3 falls the circuit is broken. The 45 shutter must be resting on the armature 5 to make it possible to close the circuit in the manner above described.

The above mentioned improvements may be used on motion picture machines which 50 are equipped with fire prevention attachments without interference with any attachments already on the machines or they can be used on machines which have no fire prevention attachments.

55 Provision is also made to stop the motor in case of accident. For this purpose a make and break contact is provided in the current wire for the motor. A plate 32 is mounted on and insulated from the cone 60 2. A contact post 35 is made rigid with the plate 32 and an arm 33 is pivotally mounted on the plate 32 which may be porcelain. The arm 33 carries a lug 34 adapted to engage the post 35. This arm 33 is projected into the path of the shut 65 so that

when the shutter falls, the arm 33 will be moved by the shutter and the lug 34 will leave the post 35, thus breaking the motor current. The motor current wire is interrupted and one end 30 is connected to the 70 arm 33 and the other arm 31 is connected to the post 35 so that when the arm 33 is moved and the lug 34 moved away from the post 35, the current will be broken so that the motor will stop. When the shutter 3 is 75 raised the arm 33 will be restored to bring the lug 34 in contact with the post 35. A spring 37 is attached to the arm 33 and to the post or lug 36 so that the spring will expand and throw the arm 33 to normal position.

What I claim, is,—

1. In a motion picture machine provided with a film operating motor and a circuit therefor and an electric lamp and a housing therefor, safety attachments for said machine comprising a gravity-closing shutter pivotally mounted on said lamp house, an electro-magnet, an armature therefor supporting said shutter, a wire connecting 85 one pole of said magnet with a supply source of electricity, one pole of said magnet being grounded on the machine frame, contacts mounted on and insulated from said machine frame, a wire connected to said machine frame and to said contacts, and means on said machine frame for automatically grounding one of said contacts with the machine frame including parallel 90 guide plates for the film, one of which is 100 electrically connected to the machine frame and the other electrically connected to a supply source of electricity and normally held insulated from the first main guide-plate by the film and adapted to contact 105 therewith when the film breaks, whereby said magnet is energized and said shutter is dropped to cut off the light.

2. In a motion picture machine provided with a film-operating motor and a circuit 110 therefor and an electric lamp and a housing therefor, safety attachments for said machine comprising a gravity-closing shutter pivotally mounted on said lamp house, an electro-magnet mounted on said lamp house 115 and an armature therefor supporting said shutter, one pole of said magnet being grounded with said machine frame and a wire connecting the other pole of said magnet with a supply source of electricity, contacts on said machine frame and a wire connecting said contacts to said source of electricity, and means for automatically grounding one of said contacts with the machine frame should the film break including 120 parallel guide plates one of which is grounded on the machine frame and the other normally held insulated therefrom by the film and adapted to contact therewith and electrically connected to a supply source of 125 130

electricity whereby said magnet will be energized and said shutter dropped.

3. In a motion picture machine provided with a film-operating motor and a circuit therefor and an electric lamp and a housing therefor, safety attachments for said machine comprising a gravity closing shutter pivotally mounted on said lamp house, an electro-magnet mounted on said house and 5 an armature therefor supporting said shutter, one pole of said magnet being grounded with the machine frame and a wire connecting the other pole of the magnet to a supply source of electricity, contacts on 10 the machine frame and a wire adapted to connect said contacts to said source of electricity, means for automatically grounding

one of said contacts with the machine frame should the film break including parallel guide-plates for the film one of which is 20 grounded on a machine frame and the other electrically connected to a supply source of electricity and movable and normally insulated from the grounded plate by the film and springs for pressing said movable plate 25 against said grounded plate should the film break whereby said magnet is energized and said shutter is dropped to cut off the light, and means actuated by the shutter when falling for breaking said motor circuit. 30

In testimony whereof, I set my hand this 17 day of April, 1917.

DAVID P. DODD.
